FIG. 1

The design is characterized by a generally squared central portion, with the corner portions of the saucer being disposed essentially in a plane parallel with the central portions of the saucer.

I claim:

The ornamental design for a saucer, substantially as shown and described.
